UNITED STATES PATENT OFFICE.

LOUIS H. BRINKMAN, OF WEST HARTFORD, CONNECTICUT, ASSIGNOR TO WHITLOCK COIL PIPE COMPANY, OF WEST HARTFORD, CONNECTICUT, A CORPORATION OF CONNECTICUT.

APPARATUS FOR BENDING PIPE.

SPECIFICATION forming part of Letters Patent No. 785,082, dated March 21, 1905.

Application filed August 6, 1904. Serial No. 219,699.

To all whom it may concern:

Be it known that I, LOUIS H. BRINKMAN, a citizen of the United States, residing at West Hartford, in the county of Hartford and State of Connecticut, have invented a new and useful Improvement in Apparatus for Bending Pipe, of which the following is a specification accompanied by drawings forming a part of the same, in which—

Figure 1 is a plan view of so much of the apparatus as is necessary to illustrate the nature of my invention. Fig. 2 is a vertical sectional view on the plane of 2-2, Fig. 1. Fig. 3 is a plan view of the parts shown in Fig. 1, but in their relative position when a pipe has been bent. Fig. 4 is a sectional view on line 4, Fig. 1; and Fig. 5 is an end view of the reciprocating former.

Similar reference-figures refer to similar parts in the different views.

The object of my present invention is to provide an apparatus for bending pipe by which the stretching of the outer side of the bent section of the pipe is obviated; and it consists in the construction and arrangement of parts, as hereinafter described, and pointed out in the annexed claims.

Referring to the accompanying drawings, 1 denotes a table provided on its upper face with a groove 2 for a reciprocating former 3, mounted upon the end of a rod 4, to which a longitudinal movement is imparted by any suitable known mechanism. (Not shown.) The former 3 is provided with parallel sides 5 and a rounded end 6, corresponding to the desired curvature of the pipe. The parallel sides 5 and the rounded end 6 are provided with a semicircular groove 7, adapted to fit the side of the pipe to be bent. Mounted upon the table 1 are a pair of mandrels 8 9, with their outer ends held in the upturned brackets 10 upon the outer ends of swinging arms 11. The mandrels 8 and 9 may be conveniently held in the brackets 10 by providing the outer ends of the mandrels with screw-threads 12 and clamping-nuts 13 14, said nuts being squared and clamped against the flat sides of the brackets 10 to hold the inner free ends 15

15 of the mandrels in a horizontal position and preferably with a short space 16 between the inner ends of the mandrels.

The inner ends of the arms 11 are transversely adjustable on plates 17, said plates 17 being provided with ways 18 and carrying clamping-bolts 19, extending through elongated slots 20 in the arms 11 and being provided with clamping-nuts 21. The plates 17 are pivoted on bolt-heads 22, carried by plates 23, which are supported by the table 1 and are capable of adjustment thereon in a groove 24 at right angles to the groove 2. The plates 23 are held in position by bolts 25, extending through slots 26 in the table 1 and carrying clamping-nuts 27. Each of the arms 11 is therefore adjustable in two directions—namely, in the groove 24 in a line at right angles to the movement of the former 3 and also on the plates 17—to vary the position of the arm 11 relatively to its bolt-head 22. The arms 11 at their inner ends are provided with upturned flanges 28 at right angles to the upper surface of the arms 11 to form a bearing-surface for the outer side of the pipe to be bent and resist the bending strain applied to the pipe. Adjustably mounted upon each of the arms 11 are angular stop-plates 29, which are adjustably clamped to the arms by bolts 30, extending through an elongated slot 31 in the arm 11 and carrying a clamping-nut 32. The stop-plates 29 are slotted at 33 for convenience in inserting and removing the mandrels 8 and 9.

The pipe 34 to be bent is shown in sectional view in Fig. 2 and in full in Fig. 3, and its position is indicated by the broken lines 35 in Fig. 1. The inner ends 15 of the mandrels 8 and 9 are spherical in shape and of sufficient size to substantially fill the interior of the pipe, as represented in Fig. 2. The mandrels are inserted in the opposite ends of the pipe and firmly attached to the upturned brackets 10 of the swinging arms. The stop-plates 29 are then adjusted on the arms to bear against the opposite ends of the pipe and hold it centrally on the mandrels. Power is then applied to the push-rod 4 to slide the

former 3 along the groove 2 from the position shown in Fig. 1 to that shown in Fig. 3. The advance movement of the former 3 against the central section of the pipe as it is held upon the mandrels 8 and 9 causes the arms 11 11 to swing on their bolt-heads 22 into the position shown in Fig. 3 and the central section of the pipe to be bent around the curved end 6 of the former 3. The swinging arms 11 are adjusted on the plate 17 and relatively to the bolt-head 22, so the axis of rotation of the arms 11 will correspond substantially with the outer side of the pipe, so that as the pipe is bent around the curved end of the former the only deforming strains applied to the pipe are those which upset the metal on the inner side of the pipe during the operation of bending, and the stretching strain, which would tend to elongate the outer side of the pipe, is entirely avoided. If the pipe 35 were to be bent by forcing it around the curved end of the former by pressure applied to its opposite ends, it is obvious that the inner side of the pipe, which would be shortened in the act of bending, would be upset and that the outer side of the pipe, which would be elongated in the act of bending, would be stretched. The stretching of the outer side of the pipe reduces the thickness of the pipe, and consequently weakens it, and it is the object of my invention to obviate this injurious stretching of the outer side of the pipe, which I accomplish in my present apparatus by supporting the pipe upon mandrels carried by the swinging arms 11 11 and controlling the swinging movement of the arms on axes lying substantially in the plane of the outer side of the pipe. As it may be desirable to bend pipes of different sizes in the same apparatus, I have provided two adjustments of the arms 11 11 to accommodate different sizes of pipe and also to allow formers of different sizes to be used.

What I claim as my invention, and desire to secure by Letters Patent, is—

1. In an apparatus for bending pipe, the combination with a former, of a pair of swinging arms, a pair of mandrels held by said arms in alinement with each other, with the opposing ends of said mandrels free to enter opposite ends of the pipe to be bent, and means for applying a bending strain to a pipe held on the free ends of said mandrels.
2. In an apparatus for bending pipe, the combination of a former, a pair of mandrels held in alinement with each other, with the opposing ends of the mandrels free to enter the opposite ends of the pipe to be bent, each of said mandrels being capable of a swinging movement about an axis substantially coincident with the side of the pipe opposite the former, and means for applying a bending strain to a pipe held on said mandrels by which the pipe is wrapped around said former.
3. In an apparatus for bending pipe, the

combination with a former, a pair of mandrels held from longitudinal movement and in alinement with each other, with the opposing ends of said mandrels free to enter the opposite ends of the pipe to be bent, a pair of pivoted arms supporting said mandrels, and means for adjusting the axes of said pivoted arms relatively to the pipe held on said mandrels, and means for bending said pipe around said former.

4. In an apparatus for bending pipe, the combination with a former, of a pair of mandrels held in alinement with each other, with the opposing ends of the mandrels free to enter the opposite ends of the pipe to be bent, means for adjusting a pipe longitudinally on said mandrels, and means for wrapping a pipe held on said mandrels around the former.

5. In an apparatus for bending pipe, the combination with a pair of mandrels in alinement with each other, and having their opposing ends free to enter the opposite ends of the pipe to be bent, a pair of holding-arms for said mandrels capable of a swinging motion, and a reciprocating former by which a bending strain is applied to a pipe held on said mandrels.

6. In an apparatus for bending pipe, the combination with a pair of mandrels held in alinement, with the opposing ends of said mandrels free to enter the opposite ends of the pipe to be bent, said mandrels being capable of a swinging movement in opposite directions, and a reciprocating former adapted to apply a bending strain to a pipe held on said mandrels.

7. In an apparatus for bending pipe, the combination of a pair of mandrels held in alinement, with their opposing ends capable of entering the opposite ends of the pipe to be bent, a reciprocating former adapted to apply a bending strain to a pipe held on said mandrels, said mandrels being capable of a swinging movement in opposite directions about axes at right angles to the plane of said reciprocating former.

8. In an apparatus for bending pipe, the combination with a reciprocating former, of a pair of mandrels held in alinement with each other in a line at right angles to the line of movement of said former, said mandrels being capable of a swinging movement, and means for adjusting the axes of rotation of said mandrels.

9. In an apparatus for bending pipe, the combination with a table having ways for a reciprocating former, of a reciprocating former, a pair of swinging arms pivotally held on said table, brackets on said arms and mandrels held in said brackets, with their free ends adapted to enter the pipe to be bent.

10. In an apparatus for bending pipe, the combination with a table having ways for a reciprocating former, of a reciprocating former, a pair of swinging arms pivotally held

on said table, brackets on said arms, mandrels held in said brackets with their free ends adapted to enter the pipe to be bent, and means for longitudinally adjusting said mandrels in 5 said brackets.

11. In an apparatus for bending pipe, the combination with a table having ways for a reciprocating former, of a reciprocating former, pivots for a pair of swinging arms, 10 means for adjusting said pivots relatively to said former, swinging arms on said pivots, and mandrels held by said swinging arms.

12. In an apparatus for bending pipe, the combination with a table provided with ways for a reciprocating former, of a reciprocating former, swinging arms pivotally mounted on said table, means for adjusting said arms relatively to said former, means for adjusting said arms relatively to their axes of rotation and 20 mandrels carried by said arms.

13. In an apparatus for bending pipe, the combination with a reciprocating former, of a pair of swinging arms, means for adjusting said arms relatively to said former, means for 25 adjusting said arms relatively to their axes of rotation and mandrels carried by said arms.

14. In an apparatus for bending pipe, the combination with a reciprocating former, of

a pair of swinging arms, a pair of mandrels carried by said arms and adapted to enter the 30 opposite ends of the pipe to be bent, the axes of said swinging arms substantially coincident with one side of a pipe held on said mandrels.

15. In an apparatus for bending pipe, the 35 combination with a pair of mandrels held in alinement and arranged to enter the opposite ends of the pipe to be bent, of a reciprocating former adapted to apply a bending strain to a pipe held on said mandrels and flanges arranged to bear against a pipe held on said mandrels and to resist the bending strain exerted by said former.

16. In an apparatus for bending pipe, the combination with a reciprocating former, of a 40 pair of swinging arms, mandrels carried by said arms, and adapted to enter the opposite ends of the pipe to be bent, and stops adjustably held on said arms and adapted to bear against the ends of the pipe.

Dated this 3d day of August, 1904.
